J. G. WEBB.
METHOD AND APPARATUS FOR ELECTRICALLY REDUCING REFRACRYORY SUBSTANCES.
APPLICATION FILED MAR. 16, 1917.

1,234,836.

Patented July 31, 1917.

UNITED STATES PATENT OFFICE.

JOHN G. WEBB, OF RICHMOND, VIRGINIA.

METHOD AND APPARATUS FOR ELECTRICALLY REDUCING REFRACATORY SUBSTANCES.

1,234,836.

Specification of Letters Patent. Patented July 31, 1917.

Application filed March 16, 1917. Serial No. 155,297.

To all whom it may concern:

Be it known that I, JOHN G. WEBB, a citizen of the United States, residing at Richmond, in the county of Henrico, State 5 of Virginia, have invented certain new and useful Improvements in Methods and Apparatus for Electrically Reducing Refractory Substances; and I do hereby declare the following to be a full, clear, and exact description of the invention, such as will enable others skilled in the art to which it appertains to make and use the same.

This invention relates to a method and apparatus for reducing metals through the 15 medium of an electric arc, the object of the invention being to utilize a maximum percentage of heat induced in the work of reduction with a corresponding saving in heat units that are otherwise wasted and with 20 also a corresponding saving of the refractory lining of the furnace that has been previously burned out by these waste units.

The method embodies the maintenance of the reducing arcs in such relation to the 25 mass operated upon as will form a depression in the mass into which the electrodes that sustain the arc, are gradually lowered as the fusing operation serves to deepen the depression, so that the arc or arcs as 30 the case may be, are surrounded by a wall of the mass under reduction and thus the mass absorbs the heat units so that they are utilized in attaining the objective, instead of then passing to the refractory lining of 35 the furnace with its resultant deterioration, as occurs in the usual practice of the electric reduction. The apparatus is designed to permit of the practice of the method referred to.

40 In the drawings;

Figure 1 shows an electric furnace in circuit with a three phase generator, the furnace having a full charge of material to be reduced and the electrodes being in position above the charge to sustain the arcs as 45 initially struck.

Fig. 2 is a view similar to Fig. 1 and showing a depression of crater formed in the mass as the reduction progresses and 50 showing how the mass incloses the arcs so as to receive the impingement of heat units that would be absorbed by the lining of the furnace if the arcs were not thus inclosed.

Fig. 3 is a view similar to Fig. 2 and having added in dotted lines the relation of

the electrodes to the charge in the ordinary electric furnace wherein the lowermost electrodes are in substantially horizontal position.

Fig. 4 is a detail view partly in section and partly in elevation and showing the mounting of one of the electrodes to permit of its longitudinal feed and to effect lateral swinging adjustment.

Fig. 5 is a detail sectional view taken transversely of an electrode and with the pivotal mounting of the electrode in plan view.

Referring now to the drawings, there is shown at 10 the body of a furnace having 70 a refractory lining indicated at 11. It will be noted that the greatest width of the receiving chamber 12 of the furnace is somewhat greater than its height, these proportions having been found best for concentrating 75 the heat against the charge 13, it being understood that the higher the chamber of the furnace the greater the exposed area of lining above the charge and the greater the consequent opportunity for heat absorption by the lining. Usually the top of the chamber is comparatively high above 80 the charge and is so located, as to relieve it of the intense disintegrating effect of the heat from the arc. With the particular 85 arrangement of electrodes and in the practice of my particular method, however, the heat units from the arc do not rise in sufficient quantity to the roof of the chamber to disintegrate its lining at anything near 90 the rate resultant with the usual arrangement of electrodes hereinafter more particularly referred to.

As illustrated, the top of the furnace 14 forming the roof of the chamber 12 is 95 sprung on an arc of considerable radius so as to make its higher portion little above the upper edge of the side wall.

The furnace illustrated is built to utilize a three phase current and includes three 100 electrodes 15, 16 and 17 which are brought each through an insulating bushing 18 in the top of the furnace. The electrode 16 is shown as coinciding with the vertical axis of the furnace while the electrodes 15 and 17 converge downwardly at opposite sides of the electrode 16 and at equal angles thereto. This particular arrangement of the electrodes in the same transverse plane is a matter of convenience in the manipula- 110

tion of the electrodes hereinafter explained and it will of course be understood that the electrodes may be equidistant if preferred.

Each electrode is longitudinally adjustable through its bushing 18 and each one is provided with a metallic collar 19 held thereon by a set screw 20 or in any other desired way and to each, is connected a bail 21 to which in turn is attached a cable 22 that passes over suitable direction pulleys 23 and 24 to a windlass 25 upon which the cable may be wound to raise its corresponding electrode, it being understood that the electrode will move downwardly by gravity when the windlass is moved in an unwinding direction. Each electrode, it will be noted, is passed slidably through its insulating bushing 18 and the bushings of the electrodes 15 and 17 are each provided with an encircling band 40 having trunnions 41 rockingly mounted in a support 42. The openings 43 in the furnace top and the registering openings 44 in the furnace lining through which the electrodes enter the furnace, are of sufficient size to permit of oscillatory movement of the electrodes 15 and 17 toward and away from the electrode 16 to maintain a determined length of arc between each pair of electrodes at different elevations of the latter and to permit of distribution of the direct influence of the arcs over different areas of the crater bottom.

Any desired mechanism of course may be used for mounting the electrodes to permit of this adjustment. To swing the bushings on their trunnions, hand operated screws 45 may be connected with collars 46 carried by the bushings.

40 The feed wires 26, 27 and 28 from a three phase generator 29 are in circuit with their corresponding electrodes 15, 16 and 17 through the medium of the collars 19 to which they are connected.

45 Referring now more particularly to Fig. 1 of the drawings, when the furnace is to be charged, with scrap iron, for instance, the charge is introduced through the door opening 30, at which time the electrodes are raised above the upper line of the door so as not to be struck and injured as the charge is thrown into the furnace. When the charge, indicated at 13, has been completed, the electrodes are thrown into circuit with the generator 29 through the medium of a suitable switch 32 while the electrodes are then above the charge, the electrodes being so spaced as that at this time they will not arc across. Through the medium of the windlass 25, the electrodes are then lowered simultaneously to contact the charge and are then instantly raised to a degree to strike arcs between the electrodes and the charge, the ammeters 33, 34 and 35 in the circuits of the electrodes 15, 16 and 17 respectively,

being observed and the electrodes being manipulated to throw as even a load on the generator and to maintain the arcs as uniform as may be.

Immediately the arcs are struck, the portions of the charge sustaining the arcs in connection with the electrodes, begin to melt and as they melt they settle with resultant craters. The electrodes are lowered gradually to compensate and the process continues until the individual craters merge and become one crater which grows deeper as the operation continues and into which the electrodes are further lowered.

When the electrodes shall have convergingly approached one another and the gases rising from the charge have in conjunction established the essential condition, the arcs swing to include the electrodes in multiple with the charge instead of in series as initially, so that the molten metal at the bottom of the crater is overspread with a flaming arc which is held in close impingement against the molten metal by reason of the conductivity of the metal.

It will be noted that the angle of the electrodes 15, 16 and 17 to the vertical is less than the angle of repose of the charge. This is of importance in order that divergence of the wall of the crater from the electrodes 15 and 17 may be insured and thus it may be possible that arcs may be maintained between the charge and the extremities of the electrodes only. It will be readily seen upon reference to Fig. 3 of the drawings that if the lower electrodes were arranged in the horizontal positions illustrated, as soon as a crater were formed beneath the terminals of the electrodes and the bed of that crater sunk to such a degree that the resistance from the electrodes through the gasses to the bottom and wall of the crater were greater than the resistance between the electrodes and the top of the charge, arcs would be established between the electrodes and the charge at corresponding points of the lengths of the electrodes. In other words, the arcs would creep along the horizontal electrodes or would shift to different points of the lengths of the electrodes as influenced by varying resistances between the electrodes and charge at different points of the lengths of the electrodes.

When the angles of the lower electrodes to the vertical are less than the angle of repose of the charge, then that portion of the charge forming the wall of the crater will by gravitation retain its angle of divergence from the electrodes 15 and 17 and prevent creeping of the arcs up the electrodes.

Upon reference to Fig. 2 of the drawings, it will be noted that the charge incloses the arcs and thus the heat units rising from the

arcs are absorbed by that portion of the charge forming the crater wall and it is found in practice that the heat units that rise above the charge and impinge against the lining are so few as that the lining will stand a number of heats, a multiple of those of the lining of a furnace wherein this particular arrangement of the electrodes is not had.

10 While there is shown the use of three electrodes in a three phase circuit, it will of course be understood that the number and arrangement of the electrodes may be varied at will and that they may be connected electrically as may be deemed best so long as that the angle between each electrode and the horizontal is such that there will be a divergence of the wall of the resultant crater from the surface of each electrode, thus to 15 permit of progressive deepening of the crater and a resultant inclosure of the arc or arcs. It will of course be understood that when I know the angle at which I introduce the electrodes into the crater, I will know 20 the critical voltage beyond which the arc will climb the electrodes and if I establish this angle between the electrodes less than I know by experimentation or otherwise, will be the angle of the crater wall, I insure 25 against the arcs running up the crater wall and thus I hold the arcs to the bottom of the crater, permitting the heat units to rise along the wall of the crater and gradually reduce that wall with efficiency.

30 35 It will be noted furthermore that the angle of the lower electrodes to the angle, is such that the action of gravity exerts a greater tensile strain than a transverse strain, the latter being almost negligible with the consequent safety against fracture of the carbon of which the electrodes are formed.

40 What is claimed is:

45 1. The method of melting a charge which consists in subjecting the charge to the action of an electric arc sustained by electrodes disposed in such relation to the charge as that the impingement of the arc against the charge will establish a crater, and introducing the electrodes into the crater as the latter deepens at an angle to each other less than the angle between an electrode and the wall of the crater while maintaining the arc.

50 55 2. An apparatus for reducing metals to a molten state comprising a closable hollow body adapted to receive a charge, a plurality of electrodes entering the body, means for feeding the electrodes into the body and maintaining them at such angle to each other and in such location with respect to the furnace body as to insure the angle between the electrodes less than the angle be-

65 tween either electrode and the wall of a crater that may be resultant in a charge within the furnace subject to an arc between the terminals of the electrodes and means for maintaining an electric arc between the electrodes.

3. The method of melting a charge which consists in subjecting the charge to the action of electric arcs sustained between the electrodes and the charge to establish a crater in the latter and introducing the electrodes into the crater as it is formed and at an angle to each other and simultaneously 70 approaching the electrodes toward each other to shift the arc so that it will swing between the electrodes and between the electrodes and charge in multiple while maintaining the electrodes out of all physical contact.

4. The method of melting a charge which consists in subjecting the charge to the action of electric arcs sustained between the electrodes and the charge to establish a 75 crater in the latter and introducing the electrodes into the crater as it is formed in such relation thereto as to maintain the arcs while maintaining the electrodes out of all physical contact.

90 95 5. The method of melting a charge which consists in subjecting the charge to the action of a plurality of electric arcs sustained each between an electrode and the charge to establish a crater in the latter, introducing each electrode into its crater as it is formed and out of physical contact with the charge, in both its molten and unmolten state and simultaneously approaching the electrodes toward each other to merge the craters and 100 shift the arc so that it will swing between the electrodes and between the electrodes and charge in multiple.

6. An apparatus for reducing metals to a molten state comprising a hollow completely 105 closable body adapted to receive a charge, a plurality of electrodes entering the body, means for maintaining an electric arc between the electrodes, an ammeter in the circuit of each electrode and means for adjusting the electrodes with respect to each other and with respect to a charge within the body to insure the angle between the electrodes less than the angle between either electrode and the wall of a crater that may be resultant 110 in the charge subject to the arc between the terminals of the electrode.

115 In testimony whereof, I affix my signature in the presence of two witnesses.
